UNITED STATES PATENT OFFICE.

WILLIAM HUMANS, OF CAMBRIDGE, MASSACHUSETTS, ASSIGNOR TO THE AMERICAN MAGNETIC ELECTRIC COMPANY, OF JERSEY CITY, NEW JERSEY.

MAGNETIC ANNUNCIATOR.

SPECIFICATION forming part of Letters Patent No. 388,876, dated September 4, 1888.

Application filed July 23, 1885. Serial No. 172,435. (No model.)

To all whom it may concern:

Be it known that I, WILLIAM HUMANS, of Cambridge, in the county of Middlesex and State of Massachusetts, have invented a new and useful Magnetic Annunciator, of which the following is a specification, reference being had to the accompanying drawings, in which—

Figure 1 is a front elevation of one of my annunciators, showing sixteen drops or numbers. Fig. 2 is a side view of one form of drop embodying my invention. Fig. 3 is a rear view, and Fig. 4 a lengthwise section of Fig. 2, and shows also a circuit and circuit-closer. Fig. 5 is a perspective detail of the armature and its connections. Figs. 6 and 7 illustrate a modification.

Annunciators are usually made in one of three ways—viz., the number is upon a stationary plate and there is a cover in front of the number, which cover is held in that position until opened by the index of the armature, the removal of the cover disclosing the number, and the cover is then replaced by hand or by some appropriate mechanism, commonly called a "drop-raiser;" second, the index carries a piece of sheet material with the number upon it, and is so arranged with relation to a cover that the number is visible when in one position and not visible when in another position, this being the converse of the first way—that is, in the first way the cover is moved to disclose the stationary number, while in the second way the cover is stationary and the number is moved in order to become disclosed. The third way is to use the index simply to call attention to the number.

My invention is of course applicable in annunciators on all these plans; but I have shown it in Figs. 1 to 4 as applied to cause the cover to move in order to disclose the number, and in Figs. 5, 6, and 7 as applied to cause the number to move either behind a cover with suitable apertures or simply as an index, as in the third way above mentioned.

In the drawings, A is a magnet, and a its armature, the armature being mounted on its axis, as clearly shown in Figs. 2, 3, and 4. The armature is preferably constructed as described in an application for patent filed by

me, Serial No. 172,433, July 23, 1885; but, as it may be constructed in the usual way, it is not necessary to describe it in detail. The frame which supports the armature is made up of the cross-pieces b b', which are connected by the rods b², thereby making the armature and its supporting-frame so that the whole can be readily inserted between the poles of the magnet, the head b' centering one end of the armature, and the connection being completed by inserting the cross-piece b in the recesses in the poles of the magnet. This makes a simple and exceedingly cheap and durable device which can be readily put together with extreme accuracy by ordinary workmen, and this combination of an armature with its magnet by means of the cross-pieces b b', connected by the rods b², constitutes one feature of my invention.

The cross piece or head b' has ears upon it, which serve as bearings for the index D, which in Figs. 1 to 5, both inclusive, is a lever, the inner end of which is in a groove in the end piece, d, of the armature, and the outer end of which is a latch which holds the cover F in place. The index D is adjusted in this form of my drop by the light spring d', which is carried by the block d², and this block is adjustable by the set-screw d³. (See Fig. 2.) The index D extends through a slot in the neutral portion of the magnet, as shown in Fig. 4. I prefer to make a double catch on the index and on the cover F, so that in case the armature shall be attracted to either side the cover will be held up by the catch. The spring d' and this double catch are precautionary, for obviously a counter-weight on the lever or on the armature will answer instead; but where feeble alternating currents are to be used counter-weights and springs are undesirable, and in such cases the double catch is important.

In Figs. 6 and 7 the index D is in one piece with the end piece, d; but the construction is otherwise the same as that above described.

Another feature of my invention relates to the connections between the armature-coil and line, and consists in carrying one end of the coil to the insulating-block f¹, which is firmly attached to the cross-piece b and the magnet

A, and has a wire, f , secured to it, which is held in contact with the end of the wire from the coil by the screw f' , (which is of course out of contact with the magnet A.) The other end 5 of the wire from the coil is in electrical connection with the cross-piece b . The springs $f^2 f^3$ are attached to the wooden shelves H of the casing of the annunciator, and are electrically connected to the line-wire. Consequently 10 when the armature and its supporting frame are put in place between the legs of the magnet one spring, f^2 , will bear upon the electrode f and the other spring, f^3 , will bear upon the end of the cross-piece b , as clearly 15 shown in Fig. 4, and thus the armature-coil will be connected to line in a very simple and perfect manner.

The packing together of a series of my drops, as shown in Fig. 1, with like poles to 20 like poles makes one compound magnet of all the drops, and thus increases the magnetic energy of the magnet of each drop, thereby considerably increasing the efficiency of each drop and making each sensitive to very feeble 25 currents.

The part G, to which the cover F is hinged, is shown as secured to the shelves H, but may of course be secured only to the magnet A. In 30 Fig. 4 it is shown secured to the magnet by lips g , which are bent into a recess in the magnet.

It will be observed that when the armature and its frame are supported by the magnet, as clearly shown in Figs. 2, 3, and 6, the device 35 is very compact and strong, and a number of them can be readily packed together or arranged upon a back board.

I have shown the index finger at right angles to the axis of the armature; but that is not 40 essential, as will be clear to all familiar with this art.

The tablet J in Figs. 1 to 4, inclusive, is inserted in a recess formed in the magnet and covered by the front G, and is pressed forward 45 close against the rear surface of front G by the spring j . This is in order that the tablets may

be shifted readily, and constitutes a feature of my invention.

The operation is as follows: The battery-circuit shown in Fig. 4 is kept open normally 50 and closed by the ordinary push-button, too well known to require description. When the current passes, the bell shown in Fig. 4 sounds, and the lever D is moved by the partial rotation of the armature on its axis, unlatching 55 door F, which discloses the number of the room, as indicated in Fig. 1.

In Fig. 4 the door remains open until closed by the attendant and caught again by the latch on the end of the lever D. 60

In Figs. 6 and 7 the armature may be operated by alternating currents and may stand normally, as shown in Fig. 6; or it may be moved in one direction by making the battery-circuit and returned by the usual drop-raiser. 65

What I claim as my invention is—

1. In combination, magnet A, armature a , head b' , cross-piece b , and rods b^2 , the magnet being rounded inside to receive the head b' and recessed to receive the cross-piece b , all substantially as set forth. 70

2. In combination, magnet A, its armature a , cross-piece b , insulating-block f^4 , electrode f , shelves H H, and connecting-springs $f^2 f^3$, the springs $f^2 f^3$ being fast, respectively, to the shelves H H and connected to the line-wire, so that putting the magnet and its armature in place between shelves H H connects the coil of the armature to line, substantially as 75 described. 80

3. An annunciator having a series of permanent magnets arranged with like pole to the like poles of the neighboring magnets, the magnets being substantially uniform in size and shape, and each magnet having its armature 85 arranged within and supported by it, substantially as described.

WILLIAM HUMANS.
